CLAIM

The ornamental design for a vehicle storage unit, as shown and described.

DESCRIPTION

FIG. 1 is a diagrammatic perspective view of a vehicle storage unit;

FIG. 2 is a front elevational view thereof;

FIG. 3 is a rear elevational view thereof;

FIG. 4 is a left side elevational view thereof, the right side

FIG. 5 is a top plan view of the vehicle storage unit; and,

FIG. 6 is a bottom plan view thereof.
